GAME APPARATUS

Milton E. Wood, Eltingville, N. Y.

Application February 10, 1937, Serial No. 124,991

2 Claims. (Cl. 273—102)

This invention relates to game apparatus and more specifically to an amusement device which embodies many novel features of construction and combinations and arrangements of parts, all 5 of which will be more fully hereinafter described and pointed out in the claims.

In the accompanying drawings—

Fig. 1 is a view in vertical longitudinal section illustrating my improved apparatus, the view 10 being taken on the line 1—1 of Fig. 2;

Fig. 2 is a view in vertical section on the line 2—2 of Fig. 1;

Fig. 3 is an enlarged view in elevation illustrating the mechanism for operating the segmental electric contact which controls the lights of the apparatus;

Fig. 4 is a view in section on the line 4—4 of Fig. 3;

Fig. 5 is a fragmentary sectional plan view 20 showing the manner of connecting the coin slide with the lever for operating the several mechanisms of the apparatus;

Fig. 6 is a perspective view of the apparatus;

Fig. 7 is a fragmentary view in longitudinal 25 section showing the arrangement of lamp sockets, lamps, and compartments therefor;

Fig. 8 illustrates diagrammatically an electric circuit which may be successfully employed in my apparatus;

Fig. 9 is a perspective view of a bean bag such 30 as employed in playing the game.

10 represents the casing of my improved apparatus which is provided in the upper portion of its front 11 with an opening 12 through which 35 bean bags, such as illustrated at 13, are adapted to be thrown, and below this opening 12 an inclined shelf 14 is secured to the front 11 and directs bean bags which strike the front of the casing and miss the opening and fall thereon into 40 and through an opening 15 in the front 11 which extends throughout the width of the front. This shelf 14 is preferably connected to the front by hinges 16 and is held in operative position by detachable chains 17. This shelf 14 directs the 45 bean bags into the interior of the casing into a hopper 18 which is provided with a sliding gate 19 which when opened permits the bean bag to fall from the hopper and move outside of the casing through an opening 20 in the end wall of 50 the casing.

Bean bags which are successfully thrown through the opening 12 enter a small compartment 21 and fall down through the same upon a trap door 22. This trap door is in the form of a bell crank lever hingedly connected at its angle

as shown at 23, and one member 24 of the trap door is provided with an electric contact 25 which when moved by the fall of the bean bag is adapted to engage a fixed contact 26, and a stop 27 is provided to limit the movement of the trap door 5 and hold it in normal position. Below this trap door 22 an inclined chute 28 is provided which directs the bean bags falling thereon into the hopper 18.

The casing 10 is provided, preferably at the 10 upper portion thereof and at its front, with a horizontal series of pockets 29 having transparent fronts 30 containing numerals, there being ten of these pockets and the numerals, of course, are from "1" to "10". The casing 10 back 15 of these pockets 11 is provided with a metal bar 31, which is electrically connected with a series of sockets 32 into which electric bulbs 33 are removably located. Each of these sockets 32 at its central contact is connected by a wire 34 with an electric contact 35, there being a curved series 20 of these contacts 35 secured to a block of insulation 36 in the casing.

37 represents a segmental electric contact which is secured to a ratchet wheel 38, the latter 25 mounted to turn on a supporting stud 39, which latter is fixedly secured within a supporting plate 42 secured within the casing. A coil spring 40 connects the segmental contact 37 with a fixed pin 41, which spring is adapted to return the 30 segmental contact to normal position, a stop 42' being provided to limit the movement of the segment. The ratchet wheel 38 is so constructed as to omit any teeth from a portion of the wheel and in effect constitutes a segmental ratchet 35 wheel. This ratchet wheel is caused to move by a lever 43 pivotally supported between its ends on a pin 44 secured to the plate 42, and at its free end carrying a pawl 45. This pawl 45 is pivoted between its ends on a pin 46 secured to 40 lever 43, and a coil spring 47 connects one end of the pawl 45 with a fixed pin 48 on lever 43. 49 represents a dog which is pivotally connected by a pin 50 to plate 42, and is held by a coil spring 51 in engagement with the teeth of the 45 ratchet wheel 38, the function of this dog being to prevent accidental retrograde movement of the ratchet wheel. The lever 43 above described is connected at its lower end by a coil spring 52 with a fixed pin 53 on plate 42, and this spring 50 tends to move the lever in a direction to move the pawl 45 away from the ratchet wheel 38.

54 represents a solenoid, the armature 55 of which is pivotally connected to the lower portion of lever 43 by a pin 56, so that when the solenoid 55

is energized it operates to move the lever to the right of Fig. 3 and in a direction opposed by the spring 52 to move the pawl 43 a distance of one tooth on the ratchet wheel so as to move the 5 ratchet wheel and the segmental contact 37 a fixed distance.

57 represents a lever which is pivotally connected at its upper end to the casing 10, as shown at 58, and this lever intermediate its ends is provided with a finger 59 which is located in a recess 60 in a coin slide 61 which projects outside of one end of the casing and is manually operable when the proper coin is located in the coin receiving slide. As the coin controlled mechanism 15 forms no part of the present invention, it is not necessary to describe the same in detail except to say that the slide 61 is manually drawn outward when the coin is placed in proper position therein, and then forced inwardly which causes 20 a movement of the lever 57 and drops the coin into a container 62 within the casing. To the lower end of the lever 57 one end of a chain 63 is secured. This chain is passed over idle pulleys 64 and 65 and is connected to a pin 66 on the 25 gate 19. A coil spring 67 connects the pin 66 with a fixed pin 68 on the hopper so that this spring tends to hold the gate in closed position and return it to such position when permitted.

The lever 57 is connected intermediate its ends 30 by a link 69, with a pivoted arm 70 and this pivoted arm 70 carries a shutter 71 which is movable to a position back of the opening 12 to cover said opening and is also movable to a position to uncover said opening. The lever 57 when moved to one extreme position is adapted to engage a pin 35 72 on the dog 49 to release said dog from engagement with the ratchet wheel 38 and allow the segment 37 to return to its initial position. The lever 57 is also adapted when moved to one extreme 40 position to engage the control arm 73 of a time switch 74, the movable contact member 75 of which is adapted when in one position to engage a fixed contact 76 which is connected by a wire 77 with the segmental contact 37.

45 In the casing 10 I locate a bell or other electrically operated sounding device 78, and I may locate within the casing an electric battery 79, although, of course, it is to be understood that the apparatus may be electrically connected with any 50 source of electricity represented more or less diagrammatically by the battery 79.

Having described the structural features of the apparatus, attention is now directed to the electric diagram shown in Fig. 8, which may be successfully employed in the apparatus. As will be seen 55 in this diagram one side of the battery 79 is electrically connected by a wire 80 with all of the sockets 32, the other side of said battery being connected by a wire 81 with the time switch 74. A wire 82 electrically connects wire 81 with contact 26. The trap door 22 is electrically connected by a wire 83 with the solenoid 54, the other pole of said solenoid being connected by a wire 84 with one contact 85 of the bell 78, the other 60 contact 86 of the bell being electrically connected by a wire 87 with the wire 81.

65 It is to be understood that the apparatus where employing ten electric lamps to illuminate the ten numerals is provided with ten bean bags, such as illustrated at 13, and I would call attention to the fact that bean bags are largely employed not only because when they strike the front of the casing without entering the opening they do not 70 bounce back but fall on to the shelf 15, but also

because they add interest in the playing of the game.

The operation of the apparatus is as follows. Assuming the parts to be in the position shown in full lines in Fig. 1, which is the initial position, the operator places the proper coin on the slide 41 and forces the slide inwardly which serves to drop the coin into the container 42. This movement also causes the lever 57 to move to the dotted position shown in Fig. 1, and this lever 10 during such movement serves to perform the following operation: It engages the pin 49 on the dog 50 to release the ratchet 38 and permit the segmental contact 37 to return to its initial position if it is in engagement with any of the 15 contacts 35. The lever also engages the arm 73 of the time switch 74 and causes the latter to function, which function entails a movement of the contact arm with the fixed contact member 76. The lever 57 also moves the shutter 71 to a 20 position to cover the opening 12, and it also exerts a pull on the chain 17 to open the gate 19 and allow the bean bags in the hopper 18 to escape through the opening 20 in position to be picked up by the player. All of the above referred to 25 operations of the lever 57 are caused by the inward movement of the lever, that is, to the dotted line position shown in Fig. 1.

30 After these operations take place the coin slide is drawn outward which moves the lever to the full line position shown in Fig. 1, and this permits the spring 67 to close the gate 19 and also open the shutter 71, and moves the lever 57 away from the arm 73 of time switch 74 and away from the pin 72 of dog 49.

35 The player stands a desired distance from the apparatus and throws the bean bags 13 one at a time, endeavoring to throw them through the opening 12. If he is unsuccessful the bean bag will strike the front of the casing and be directed 40 by the shelf 14 through the opening 15 into the hopper 18. If he is successful the bean bag passing through the opening 12 will fall down upon the trap door 22 and its weight will cause this trap door to swing on its pivot and bring the contact 25 into contact with the fixed contact 26. The bag will then fall onto the chute 28 and be directed into the hopper 18. When the trap door 45 serves to move its contact 25 against contact 26, it will momentarily close the circuit from the battery 79, through wire 80, wire 82, contact 26, trap door 22, wire 83, solenoid 54, wire 84, bell 78 and wire 81 to wire 81 back to battery 79. Thus the bell 78 will be momentarily sounded and the solenoid 54 will be momentarily 55 energized, and as above explained when the solenoid is energized it moves the lever 53 a distance sufficient to cause the pawl 45 to move the ratchet wheel 38 a distance of one tooth, thus bringing the segmental contact 37 into engagement with 60 the first contact 35 and thus close the circuit to the lamp socket 32 to illuminate its lamp and illuminate the numeral "1" on the front of the pocket 29. This circuit is from the battery 79, wire 80, sockets 32, wire 33 to contact 35, through segment 37, wire 71, contact 76, arm 75, and time switch 74 and wire 81, back to battery 79.

65 It is obvious that each successful throw of a bean bag through the opening 12 will operate to move the segment 37 a distance of one tooth of 70 the ratchet wheel 38, which will be sufficient to cause the segment to successively engage the contacts 35 and illuminate the numerals as above explained. Thus, if the player succeeds in throwing five bean bags through the opening, there 75

will be the first five numerals illuminated, so that the illuminated numerals will indicate at the end of the play the number of bags which have been successfully thrown. After a predetermined length 5 of time, the time switch 74 will automatically operate to break the circuit and extinguish the lights.

While I have illustrated and described what I believe to be a preferred embodiment of my invention, it is obvious that various slight changes may be made with regard to the flow and arrangement of parts without departing from my invention, and hence I do not limit myself to the precise details set forth but consider myself at 10 liberty to make such changes and alterations as fairly fall within the spirit and scope of the claims.

I claim:

1. A game apparatus including a casing of general oblong shape having a flat front vertical wall and having a missile-receiving opening in said front wall in the upper portion thereof and having a second opening in the front wall below the first-mentioned opening and at a point approximately above the bottom of the casing, said last-mentioned opening extending throughout the full width of the front wall, an inclined shelf on the front of the casing extending throughout the full width of the casing and in position to 25 direct missiles which fall thereon through the said last-mentioned opening into the casing, a hopper in the casing into which missiles which enter the casing through either of said openings are collected, said casing having an outlet open-

ing in its side wall near the lower end of the casing, and a manually operated gate on said hopper which when opened permits the missiles collected therein to fall through said outlet opening.

2. A game apparatus including a casing of general oblong shape having a flat front vertical wall and having a missile-receiving opening in said front wall in the upper portion thereof and having a second opening in the front wall below the first-mentioned opening and at a point approximately above the bottom of the casing, said last-mentioned opening extending throughout the full width of the front wall, an inclined shelf on the front of the casing extending throughout the full width of the casing and in position to direct 15 missiles which fall thereon through the said last-mentioned opening into the casing, a hopper in the casing into which missiles which enter the casing through either of said openings are collected, said casing having an outlet opening in 20 its side wall near the lower end of the casing, a manually operated gate on said hopper which when opened permits the missiles collected therein to fall through said outlet opening, a trap door above the hopper in the casing which is operated by missiles entering the casing through the first-mentioned opening, and a manually operated shutter for closing the first-mentioned opening operatively connected to the means for 25 operating the gate controlling the outlet from the hopper, whereby when said hopper gate is opened the first-mentioned opening is closed to prevent the passage of missiles therethrough.

MILTON E. WOOD.
